WEIGHTED NONAQUEOUS DRILLING FLUID

George E. Cannon and Milton Williams, Houston,
Tex., assignors to Standard Oil Development
Company, a corporation of Delaware

No Drawing. Application April 13, 1938,
Serial No. 201,724

10 Claims. (Cl. 255—1)

The present invention is directed to a non-aqueous drilling mud of high weight.

In the drilling of oil wells, especially in the Gulf Coast, considerable trouble is encountered when it becomes necessary to drill through a certain type of shale known as heaving shale which is evidently bentonitic in character. Many opinions have been expressed as to the reasons for this difficulty but it is generally acknowledged that the main reason is the effect of water on the shale, causing it to swell. Accordingly, it has been suggested to use nonaqueous drilling mud, for example, oil.

The object of the present invention is the provision of a nonaqueous drilling mud, specifically an oil base drilling mud, of greater weight and stability than has hitherto been possible of achievement. Briefly, the present invention resides in the use in drilling operations of an oil carrying an oxide of lead such as litharge. More specifically, the present invention contemplates the addition to an oil base mud containing large quantities of litharge of an agent capable of holding the litharge in suspension.

As is well known in the art of drilling wells, it is customary to circulate from the surface to the bottom of the borehole and back to the surface a drilling fluid the function of which is to lubricate and cool the drilling bit and to carry the cuttings to the surface. Ordinarily such fluids are composed of water and a suitable clay, and may or may not include a weighting material such as inorganic compounds of high specific gravity. In the practice of the present invention the same procedure is followed except that an oil base mud carrying a compound of lead is substituted for the conventional aqueous mud and, in general, the oil base muds employed according to the present invention are of greater weight than the conventional drilling fluids.

As previously indicated, the present invention contemplates broadly the use of lead compounds, such as litharge, in oil base drilling fluids. These compounds have the peculiar advantage that they are readily wettable by oil. When it is desired to make a mud of very high weight, however, it is found that these lead compounds tend to settle rapidly from the oil base, thereby rendering the drilling fluid unsuitable for use as a circulating medium for carrying out cuttings from the borehole. It has been found that this tendency to settle out is eliminated by the use of suitable quantities of fatty acids of high molecular weight and, particularly, unsaturated fatty acids, such as oleic acid. In general, fatty acids having more

than ten carbon atoms in the molecule can be employed. By this expedient it is possible to produce a mud having a density of the order of the shale to be drilled through which is one of the objectives of the present invention.

When the fatty acid is added to the suspension of lead compound in oil it produces a mixture which has the appearance of clabber, that is, the lead compound tends to agglomerate although it remains in suspension. This agglomeration can be prevented by adding to the mixture an ester of a fatty acid, such as a vegetable or animal oil. Typical of such oils which are useful in this mixture for this purpose is linseed oil.

In the following table is shown the effect of small amount of an oleic acid on a suspension of litharge of a specific gravity 8.85 in crude oil having an A. P. I. gravity of 36. The headings over the various columns render the table self explanatory.

Crude oil: Anahuac, 36 gravity A. P. I. litharge:
sp. gr. 8.85

Weight, lbs./gal.	Viscosity, gms. @ 600 R. P. M.	Oleic acid, per- cent vol- ume	Settling
16.6	Settled too rapidly	0	Immediately.
16.6	do	0.5	Do.
16.6	do	1.0	Do.
16.6	300	1.5	Stable.
18.9	Settled too rapidly	0.75	Immediately.
22.7	do	0.75	Do.
26.0	do	0.75	Do.
26.0	340	1.0	Stable.
26.0	370	1.25	Do.
26.0	400	1.5	Do.
26.0	420	1.75	Do.
26.0	470	2.0	Do.
26.0	500	2.25	Do.
26.0	550	2.5	Do.
33.0	640	1.25	Do.*

*Less than 1% in 24 hours.

As can be seen from the above table the amount of oleic acid which is necessary to render the suspension stable, decreases with the amount of lead in suspension. For example, with sufficient lead to make a mud weighing 16.6 pounds per gallon, it was necessary to add 1.5 parts of oleic acid by volume in order to produce stability. With sufficient litharge to make a 26 pound mud on the other hand, 1% by volume of the oleic acid was sufficient for stability.

In general, the fatty acid is employed in amounts varying from about 1% to 4% by volume of the drilling fluid. Of course, greater amounts can be used. When a vegetable or animal oil is

used with the fatty acid, it is generally used in equal amounts.

It is to be understood that the above specific example is merely illustrative of the broad idea embodied in the present invention of using litharge as a weighing agent in oil base muds and of increasing the stability of suspensions of lead oxide in oil by the addition thereto of fatty acids. It is intended to claim this invention as broadly as the prior art permits in the appended claims.

We claim:

1. A stable drilling fluid comprising a suspension of an oxide of lead in a petroleum oil to which has been added at least one percent by volume of a fatty acid.

2. A drilling fluid comprising a suspension of litharge in a petroleum oil to which has been added at least one percent by volume of a fatty acid.

3. A drilling fluid comprising a suspension of an oxide of lead in a petroleum oil to which has been added at least one percent by volume of an unsaturated fatty acid.

4. A drilling fluid comprising a suspension of litharge in a petroleum oil to which has been added at least one percent by volume of an unsaturated fatty acid.

5. A stable drilling fluid comprising a suspension of an oxide of lead in a petroleum oil to which has been added at least one percent by volume of oleic acid.

6. A stable drilling fluid comprising a suspension of litharge in petroleum oil to which has been added at least one percent by volume of an oleic acid.

7. A stable drilling fluid comprising a suspension of an oxide of lead in a petroleum oil to which has been added a small amount of a mixture of a fatty acid and a glyceride of a fatty acid.

8. A stable drilling fluid comprising a suspension of litharge in a petroleum oil to which has been added a small amount of a mixture of a fatty acid and a glyceride of a fatty acid.

9. A stable drilling fluid comprising a suspension of an oxide of lead in a petroleum oil to which has been added a small amount of a mixture of oleic acid and a vegetable oil.

10. A drilling fluid comprising a suspension of litharge in a petroleum oil to which has been added a small amount of a mixture of oleic acid and a vegetable oil.

GEORGE E. CANNON.
MILTON WILLIAMS.
